US0D1016382S

(12) **United States Design Patent** (10) Patent No.: **US D1,016,382 S**
(45) Date of Patent: ** Feb. 27, 2024

(54) **ATOMIZATION CORE**

(71) Applicant: **SHENZHEN ECAP TECHNOLOGY CO., LTD.**, Guangdong (CN)

(72) Inventor: **Xiangyang Liao**, Guangdong (CN)

(73) Assignee: **SHENZHEN ECAP TECHNOLOGY CO., LTD.**, Shenzhen (CN)

(**) Term: **15 Years**

(21) Appl. No.: **29/846,631**

(22) Filed: **Jul. 18, 2022**

(51) LOC (14) Cl. **27-07**

(52) U.S. Cl.

USPC **D27/162**

(58) **Field of Classification Search**

USPC D27/100–101, 162–196; D23/360, 362; D24/110, 110.4–110.6, 113

CPC A24F 40/10; A24F 40/42; A24F 40/60

See application file for complete search history.

(57) **CLAIM**

The ornamental design for an atomization core, as shown and described.

DESCRIPTION

FIG. 1 is a top, front, right side perspective view of an atomization core showing my new design;

FIG. 2 is a bottom, front, right side perspective view thereof;

FIG. 3 is a front elevation view thereof;

FIG. 4 is a rear side elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
